UNITED STATES PATENT OFFICE

MILLARD H. TONCRAY, OF DETROIT, MICHIGAN, ASSIGNOR TO HUDSON MOTOR CAR COMPANY, OF DETROIT, MICHIGAN, A CORPORATION OF MICHIGAN

DOORCHECK

Application filed January 10, 1927. Serial No. 160,202.

This invention relates to door checks, and more particularly to the provision of means for limiting the opening movement of a vehicle door and thereby relieving the door 5 hinges of the strain encountered by suddenly throwing open the door.

When doors of vehicles are opened in the presence of a strong wind, the wind often throws the door open with considerable force 10 and entirely out of one's control with the result that considerable strain is brought upon the door hinges. In order to safeguard against such occurrences, various expedients have been employed, such as the provision of 15 a flexible strap of rubber or the like the ends of which are secured respectively to the door and to the body of the vehicle. It has also been suggested to provide for this purpose a rigid link which operates in a slot in the door 20 and either is pivotally connected with the body or operates in a slot therein. The flexible straps employed for this purpose, heretofore, have been cumbersome and unsightly and have deteriorated rapidly due to the nature 25 of the material of which they were constructed. On the other hand, rigid devices which have been employed for this purpose become worn or for other reasons become loose so as to rattle and squeak.

It is the object of the present invention to 30 provide an improved device for limiting the opening movement of a door which shall be of simple construction, and easily manufactured and assembled on the door, which is of inconspicuous appearance and is normally housed 35 and concealed, and which is fixed to the part by which it is carried and otherwise arranged so that it will not wear with continued use and cause squeaks and rattle during movement of the vehicle.

In accordance with the invention, the door post or body hinge pillar is provided with an opening for permitting free movement of 45 an arm of rigid construction. This arm is rigidly secured at one end to the adjacent door pillar and is arranged and suitably constructed to move freely through the opening in the door post when the door swings. The other end of the arm is provided with suitable 50 means, such as a hook-shaped member, for

engaging an interior portion of the door post and thereby limiting the opening movement of the door.

The invention will be more clearly understood from the following description in conjunction with the accompanying drawings: in which,

Fig. 1 is a fragmentary view in perspective of a door assembly embodying the invention;

Fig. 2 is a horizontal section of the same; and

Fig. 3 is a similar view of a door assembly embodying a modified form of the invention.

In Figs. 1 and 2, a door assembly illustrative of the invention is shown which is particularly suitable for vehicles and comprises a hollow sheet metal door post or hinge pillar 5 to which body panels 7 are secured by any well-known and suitable manner. A door pillar 8 of rigid sheet metal, such as steel, carrying the door panels 9 and 10 is suitably connected to the door post 5 as by hinges 11 secured thereto by bolts 12. The wall of the door post, if desired, may be offset slightly to provide room for the hinges so that the door may close snugly. An arm 13 of steel, or other suitable material of considerable strength and rigidity, is positioned within a slot 14 in the door pillar 8 and is rigidly secured to the interior of the pillar by a screw 15. An opening 16 is provided in the door post 5 with sufficient clearance to permit movement of the arm 13 therethrough without contact therewith as the door swings. A stop device, such as a hook-shaped member 17 is provided at the free end of the arm 13 and is adapted to engage the wall of the pillar 5 adjacent the opening 16 to limit the opening movement of the door. The opening 16 in the door post is so positioned and the arm 13 so

constructed and arranged, such for example as by curvature approximately coaxial with the hinge pivot, as to permit said arm to move freely within the opening 16 as the door swings, thereby preventing rattling and eliminating any wear either of the arm 13 or upon the sides of the opening.

In Fig. 3 of the drawings, a door assembly is illustrated embodying further and modified features of the invention. This door

assembly comprises a hollow sheet metal door post or hinge pillar 20 to which a door pillar 21 is connected by a hinge 22 suitably secured to the post 20 and pillar 21 by bolts 23 and 24 respectively. If desired, the hinge 22 may be provided with a hinge cover 25 to protect it from the elements. An arm 26 is suitably secured at one end to the interior of the pillar 21 by a screw 27 so as to project from the door through an opening 28 in the door post 20 and is constructed and arranged to move freely through the opening 28 as the door swings. The free end of the arm 26 is provided with a stop 29, such as a hook-shaped member, which is adapted to engage the wall of the post 20 which is formed with a portion 30 inclined or extending towards the stop 29 to receive the thrust of the latter edgewise.

It will be seen that as the door is opened the arm 18 and the arm 26 of the door assemblies illustrated respectively in Figs. 1 and 3, will each move within its respective opening in the door post without engagement with the edges thereof until the stop or hook-shaped member engages an interior portion of the door post to limit the opening movement of the door. In these constructions, which are intended as merely illustrative of the invention, no parts of the door check are in engagement with the door post until the door is opened the maximum allowable extent. By such provisions, wear of parts is eliminated with the result that there are no squeaks or rattles produced. It will be further noted that the door check provided in accordance with the invention is of extremely simple construction which may be easily arranged and assembled upon any door assembly of this type.

What I claim is:

1. In a vehicle body, in combination, a door post, a door, a hinge connecting said parts, one of said parts being hollow and having an opening in its wall, a rigid arm rigidly secured to the other of said parts and constructed and arranged to move freely in said opening, and a stop device carried by said arm and adapted to engage the wall of said hollow part adjacent said opening when the door is fully opened to limit the opening movement thereof.

2. In a vehicle body, in combination, a door post, a door, a hinge connecting said parts, one of said parts being hollow and having an opening in its wall, a rigid arm rigidly secured to the other of said parts and constructed and arranged to move freely in said opening without engaging the edges thereof as said door is swung on said hinge, and a stop device carried by said arm and adapted to engage the wall of said hollow part adjacent said opening when the door

is fully opened to limit the opening movement thereof.

3. In a vehicle body, in combination, a door post, a door, a hinge connecting said parts, one of said parts being of hollow sheet metal construction and having an opening in its wall, a rigid arm rigidly secured to the other of said parts and constructed and arranged to move freely in said opening, and a stop device carried by said arm and adapted to engage the wall of said hollow part adjacent said opening when the door is fully opened to limit the opening movement thereof, the sheet metal of the portion of the wall engaged by said stop device being presented edgewise thereto.

In testimony whereof I affix my signature.

MILLARD H. TONCRAY.
